TABLE WITH REVERSIBLE TOP OR SIMILAR ARTICLE

Charles M. O'Leary, 525 S. Irving Blvd.,
Los Angeles, Calif. 90005

Filed Oct. 27, 1969, Ser. No. 19,725

Term of patent 14 years

Int. Cl. D6—03

U.S. Cl. D33—14

Fig. 1.

Fig. 2.

Fig. 3.

FIG. 4.

FIG. 5.

FIG. 1 is a perspective view of one side of a table with reversible top or similar article showing my new design;

FIG. 2 is a top plan view of the table illustrating the side of the reversible top that is shown in FIG. 1;

FIG. 3 is a side elevational view;

FIG. 4 is a perspective view similar to FIG. 1, but illustrating the other side of said reversible table top; and

FIG. 5 is a perspective view similar to FIG. 1, showing a second embodiment of my new design.

The sides opposite those shown in FIGS. 1, 3, 4 and 5 are substantially similar to those shown. The other side of the reversible table top of the second embodiment shown in FIG. 5 is substantially similar to the corresponding side of the reversible table top of the first embodiment as shown in FIG. 4.

The design is characterized by the fact that the top comprises a series of three similarly polygonal top members, each being slightly wider than the one beneath it,

with the fourth polygonal member of smaller transverse dimensions projecting above the level of the uppermost of these three, as best illustrated in FIG. 3.

I claim:

The ornamental design for a table with reversible top or similar article, as shown and described.
